UNITED STATES PATENT OFFICE.

JOHN A. GUSTUS AND HENRY J. ERZINGER, OF CHICAGO, ILLINOIS.

DESIGN FOR A DISPLAY-STAND.

50,619.

Specification for Design.

Patented Apr. 17, 1917.

Application filed December 7, 1916. Serial No. 135,707. Term of patent 3½ years.

To all whom it may concern:

Be it known that we, JOHN A. GUSTUS and HENRY J. ERZINGER, both citizens of the United States, residing at Chicago, in the county of Cook and State of Illinois, have invented a new, original, and ornamental Design for Display-Stands, of which the following is a specification, reference being had to the accompanying drawing, forming part thereof.

The figure is a side elevation of a display stand, showing our new design.

We claim:

The ornamental design for a display stand as shown.

JOHN A. GUSTUS.
HENRY J. ERZINGER.

Witnesses:

RUDOW RUMMLER,
M. IRENE HUTCHINGS.
